US00D810120S

(12) **United States Design Patent** (10) Patent No.: **US D810,120 S**
Lindmark et al. (45) Date of Patent: ** Feb. 13, 2018

(54) **DISPLAY SCREEN OR PORTION THEREOF
WITH GRAPHICAL USER INTERFACE**

(71) Applicant: **ARRIS Enterprises LLC**, Suwanee, GA (US)

(72) Inventors: **Henrik Lindmark**, Norrkoping (SE); **Markus Lindmark**, Norrkoping (SE)

(73) Assignee: **ARRIS Enterprises LLC**, Suwanee, GA (US)

(**) Term: **15 Years**

(21) Appl. No.: **29/570,880**

(22) Filed: **Jul. 12, 2016**

Related U.S. Application Data

(62) Division of application No. 29/478,010, filed on Dec. 30, 2013, now Pat. No. Des. 764,485, which is a division of application No. 29/372,722, filed on Jan. 3, 2011, now Pat. No. Des. 699,260.
